[57] CLAIM

The ornamental design for a telescopic clothes hanger,
as shown.

DESCRIPTION

FIG. 1 is a perspective view of the telescopic clothes hanger showing my new design in closed position;
FIG. 2 is an enlarged side elevational view of FIG. 1;
FIG. 3 is an enlarged front elevational view of FIG. 1;
FIG. 4 is an enlarged rear elevational view of FIG. 1;
FIG. 5 is a perspective view thereof in the extended
position;

FIG. 6 is a top plan view of FIG. 5;

FIG. 7 is a side elevational view of FIG. 5.
